HEAD FOR A FURROW CUTTER

Charles A. Bratton, 5961 Germaine Lane,
La Jolla, Calif.

Filed Sept. 4, 1962, Ser. No. 71,550

Term of patent 14 years

(Cl. D39—1)

FIG. 1 is a front perspective view of a head for a furrow cutter showing my new design, the top portion being broken away for convenience of illustration;

FIG. 2 is a side elevational view thereof, the lower portion of the blade being shown in section; and

FIG. 3 is a front elevational view thereof.

I claim:

The ornamental design for a head for a furrow cutter, as shown.
